UNITED STATES PATENT OFFICE.

EDWIN A. GUINZBURG, OF NEW YORK, N. Y.

SWIMMING RING.

Application filed February 27, 1925. Serial No. 12,079.

To all whom it may concern:

Be it known that I, EDWIN A. GUINZBURG, a citizen of the United States, and a resident of the city of New York, borough of Manhattan, in the county and State of New York, have invented a new and Improved Swimming Ring, of which the following is a full, clear, and exact description.

This invention relates to bathing apparatus and particularly to an improved bathing ring and has for an object to provide a construction which will be efficient and at the same time pleasing to the eye.

Another object of the invention is to provide a bathing ring particularly adapted for children wherein a hollow projecting post is provided at one point on the ring, the post being formed in the shape of some fowl or animal.

20 In the accompanying drawing—

Figure 1 is a perspective view of a swimming ring, disclosing an embodiment of the invention.

Figure 2 is a longitudinal vertical sectional view through the structure shown in Figure 1.

Referring to the accompanying drawing by numerals, 1 indicates a tubular body which may be made of rubber or other material which may be inflated and which will not deteriorate appreciably when subjected to water. In order to provide a pleasing appearance to the ring 1 for the use of children as well as adults, the ring is formed to resemble to a certain extent, an animal or fowl.

In the accompanying drawing, the ring 1

is formed with a projection 2 representing a tail and with a post 3 formed as the neck of a swan, which neck merges into a head 4. From Figure 2 it will be noted that the neck or post 3 merges into the ring 4 and forms part thereof so that when the mouth of a person is placed over the valve 5, the ring 1 may be inflated by blowing through the valve, post or neck 3 with head 4 being also inflated. The projection or tail member 2 is preferably hollow and inflatable without departing from the spirit of the invention.

In use, the ring 1 is inflated preferably until it is comparatively tight so as to give a maximum buoyancy. The device then may be used as a life ring or as a help in swimming. For use by children, it is of special advantage in that the child may grasp the neck 3 and thereby be supported more or less in a vertical position. As the neck 3 and head 4 are hollow, they will augment or add to the buoyancy of the body 1 when all the parts are completely submerged.

What I claim is:

A swimming ring acting as a combined float and toy, comprising a substantially circular hollow body having a hollow projection at one point representing the tail of a fowl and a post extending at right angles to the plane of the body at the diametrically opposite point, said post being formed as the neck and head of a fowl, and an inflating valve connected to said body, the interior of the body, tail and the post being in free communication.

EDWIN A. GUINZBURG.
